US0D1016608S

(12) **United States Design Patent** (10) **Patent No.:** **US D1,016,608 S**
(45) **Date of Patent:** **** Mar. 5, 2024**

(54) **PHARMACEUTICAL PACKAGE**

(71) Applicant: **Gilead Sciences, Inc.**, Foster City, CA (US)

(72) Inventors: **Benjamin Luke Kozub**, San Francisco, CA (US); **Brian Nilsoft**, San Carlos, CA (US); **Kevin Nguyen**, San Francisco, CA (US); **James Paul Oberhauser**, Saratoga, CA (US); **Roman Shumylo**, Dublin, CA (US); **Joseph Anthony Cordova**, Stockton, CA (US); **Jinhui Yun**, San Francisco, CA (US); **William Harold Lizor, Jr.**, San Mateo, CA (US); **Adam Hilborn**, Brooklyn, NY (US); **Jesse Arnold Fourt**, Menlo Park, CA (US); **Léo Boris Marzolf**, San Francisco, CA (US); **Pratap Uday Ganapathy**, Menlo Park, CA (US); **Brooke Genelle Thyng**, San Francisco, CA (US); **Caricia Catalani**, San Francisco, CA (US); **Soizic Porhel**, Amsterdam (NL); **Jose Angel Meza**, San Francisco, CA (US); **Steven M. Scally**, Cherry Hill, CO (US); **Mary Cassandra Lodwick**, Brooklyn, NY (US)

(73) Assignee: **GILEAD SCIENCES, INC.**, Foster City, CA (US)

(**) Term: **15 Years**

(21) Appl. No.: **29/837,856**

(22) Filed: **May 9, 2022**

(57) **CLAIM**

The ornamental design for a pharmaceutical package, as shown and described.

DESCRIPTION

FIG. 1 is a front top perspective view of a pharmaceutical package in an open configuration;

FIG. 2 is a back bottom perspective view thereof;

FIG. 3 is front view thereof;

FIG. 4 is a back view thereof;

FIG. 5 is left side view thereof;

FIG. 6 is right side view thereof;

FIG. 7 is top view thereof;

FIG. 8 is bottom view thereof;

(Continued)

FIG. 9 is a front top perspective view of the pharmaceutical package in a partially folded configuration;
 FIG. 10 is a back bottom perspective view thereof;
 FIG. 11 is front view thereof;
 FIG. 12 is a back view thereof;
 FIG. 13 is left side view thereof;
 FIG. 14 is right side view thereof;
 FIG. 15 is top view thereof;
 FIG. 16 is bottom view thereof;
 FIG. 17 is a front bottom perspective view of the pharmaceutical package in a fully folded configuration;
 FIG. 18 is a back top perspective view thereof;
 FIG. 19 is left side view thereof;
 FIG. 20 is a right side view thereof;
 FIG. 21 is front view thereof;
 FIG. 22 is back view thereof;
 FIG. 23 is top view thereof; and,
 FIG. 24 is bottom view thereof.

The dashed lines in the drawings depict portions of the pharmaceutical package that form no part of the claimed design. The dot-dash lines in the drawings depict the boundaries of the claim and form no part thereof.

The gray shading in the figures depicts a contrast of appearance.

1 Claim, 15 Drawing Sheets
